UNITED STATES PATENT OFFICE

KENT A. HAWLEY, OF BALTIMORE, MARYLAND, ASSIGNOR TO LOCKE INSULATOR CORPORATION, OF BALTIMORE, MARYLAND, A CORPORATION OF MARYLAND

INSULATOR PIN

Application filed June 4, 1926. Serial No. 113,744.

The invention relates to insulator supporting pins and mountings therefor.

The primary object of the invention, generally stated, is to provide the combination 5 with a supporting pin, of a base and saddle member therefor whereby mounting may be readily effected upon a curved or "roofed" type of cross arm.

It is well known that the insulator may be 10 secured upon the pin prior to the mounting of the latter upon a cross arm, or that the pin may be mounted upon the cross arm first, subsequently to which the insulator is screwed down tightly, or otherwise fastened, 15 the groove in the insulator being permitted to come as it will. It then becomes necessary to turn the pin and the base thereof, as a unit, to bring the insulator groove in the same direction as the transmission wire or 20 conductor so as to receive and hold the same. There is no difficulty where the pin is used in connection with a cross arm of the flat top type, but in cases where cross arms of the curved or "roofed" variety are used, there 25 is provided a saddle member which is curved to fit the cross arm and which supports the pin base. To provide a proper mounting it has been a frequent practice to provide a 30 separate seat or washer between the saddle member and the base of the pin. This has the disadvantage of involving an extra part to manufacture and handle.

It is with the above facts in view that the 35 present invention has for a more specific object the provision of a saddle member of the curved type for use on "roofed" cross arms, but having a flat bearing surface constituting a seat for the base of the pin to support the latter adequately and make it possible 40 to effect positive securing and prevent any canting of the pin without there being any necessity for the employment of any washers or other extra parts.

Another object of the invention is to provide 45 a saddle member carrying means operatively engaging and coacting with the base of the pin for holding it against relative displacement in a longitudinal direction while permitting rotary movement to bring the

groove of the insulator to the proper position.

A still more specific object of the invention is to provide a pin and mounting in 55 which the saddle member is formed with upstruck lugs extending over the peripheral portion of the pin base.

An additional object of the invention is to provide an insulator pin and mounting means therefor which will be simple and inexpensive to manufacture and assemble, easy to use, positive in action, efficient and durable in service, and a general improvement 60 in the art.

With the above and other objects and advantages in view the invention preferably 65 consists in the details of construction and the arrangement and combination of parts to be hereinafter more fully described and claimed, and illustrated in the accompanying drawings in which:

Figure 1 is a view partly in side elevation and partly in vertical section illustrating the construction, and

Figure 2 is a horizontal section through 75 the pin showing a plan view of the base and saddle member.

Referring more particularly to the drawings, the numeral 1 designates a pin which may be of any desired length and which is 80 here shown as having a tapered portion 2 terminating in a reduced extension 3 adapted to pass through a suitable hole in a cross arm, not shown, this extension being threaded for engagement of the usual securing nut 85 thereon. The pin assembly further includes a base 4 with a tapered socket 5 therein within which the tapered portion 2 of the pin has a driven fit.

The numeral 6 designates a saddle member 90 here represented as curved transversely to fit conformingly upon a "roofed" type of cross arm. The central portion of the saddle member is pressed, stamped or otherwise formed with a central upstanding portion 7 95 which has a flat, plane or horizontal top surface 8 constituting a seat for the base 4. As another feature, the saddle member is provided with retaining means engaging over the peripheral portion of the base, this re- 100

taining means being disclosed, in the present instance, as consisting of any desired number of upstruck lugs 9 which extend outwardly of the edge of the base and which have their 5 ends bent over thereonto as shown at 10.

In the use of the device it will be seen that it is applied in the same manner as other pins and after it is in position it is a simple matter to engage a suitable wrench upon the pin and 10 turn it sufficiently to bring the insulator in such position that the groove therein will extend in the same direction as the line wire for the reception thereof, subsequently to which the nut provided on the threaded ex- 15 tension is tightened to hold the parts against displacement. It will be observed that the saddle member cannot be detached from the pin without removing it together with the base, the parts being consequently held against 20 separation during handling at any stage or in shipment. Naturally as the entire device is initially assembled as indicated there will be no multiplicity of parts to be handled individually and put together when use of the 25 pin is desired, this resulting in a saving in time and labor when making installations.

From the foregoing description and a study of the drawings it will be apparent that I have thus provided a very simply con- 30 structed and inexpensive insulator supporting pin structure which may be produced readily from bar stock cut to any desired length, the amount of machining being reduced to the minimum so that the construc- 35 tion and assembly may be effected with the fewest possible operations. It is really believed that the advantages and benefits derived from the employment of such a structure will be readily apparent to one skilled in 40 the art without further explanation.

While I have shown and described the preferred embodiment of the invention and certain details of construction and arrangement, it should be understood that the disclosure 45 is merely an exemplification of the principles involved and that the right is reserved to make such changes and variations as will widen the field of utility of the invention provided such modifications constitute no departure from the spirit of the invention or the 50 scope of the claims hereunto appended.

Having thus described the invention, I claim:

1. In an insulator support, the combina- 55 tion of a saddle member adapted for engagement upon a cross arm, a pin equipped with a base and having a threaded extension passing through the saddle member, the saddle member having a seat portion for the base, and means independent of the pin on the saddle member for retaining the base thereon.

2. In an insulator support, the combination of a saddle member adapted for engagement 65 upon a cross arm, a pin equipped with a base

and having a threaded extension passing through the saddle member, the saddle member having a seat portion for the base, and means independent of the pin on the saddle member preventing relative longitudinal 70 movement of the base and saddle member, while permitting relative rotary movement thereof.

3. In an insulator support, the combination of a saddle member adapted for engagement upon a cross arm, a pin having a separate base cooperating therewith and having a threaded extension passing through the saddle member, the saddle member having a seat portion for the base, and means on the saddle member embracing the base for preventing relative longitudinal movement of the base and saddle member while permitting relative rotary movement. 75

4. In an insulator supporting structure, a saddle member having a seat portion, a pin carrying a base engaged upon the seat portion, the pin having an extension passing through the saddle member, and retaining means on the saddle member engaging over 80 the periphery of the base for preventing relative longitudinal movement of the base and saddle member, the base and pin being rotatable with respect to the saddle member and formed of separable parts. 85

5. In an insulator supporting structure, a saddle member of curved form adapted for engagement upon a roofed type of cross arm and having an upstanding flat seat portion, a pin extending through said seat portion and carrying a base rotatably engaged upon the seat portion, and elements on the seat portion engaging the peripheral portion of the base, the pin having a tapered portion, and the base having a correspondingly tapered 90 socket. 95

6. In an insulator supporting structure, a saddle member of curved form adapted for engagement upon a roofed type of cross arm and having an upstanding flat seat portion, a pin extending through said seat portion and carrying a base rotatably engaged upon the seat portion, and elements on the seat portion engaging the peripheral portion of the base, said elements being formed as clips 100 struck up from the saddle member. 110

7. In an insulator support, the combination of a saddle member adapted for engagement upon a cross arm, a pin having a separate base cooperating therewith and having a threaded extension passing through the saddle member, the saddle member having a seat portion for the base, and upstanding means on the saddle member for retaining 115 the base thereon. 120

8. In an insulator support, the combination of a saddle member adapted for engagement upon a cross arm, a pin having a separate base cooperating therewith and having an extension passing through the saddle 130

member, said extension being threaded from a point beyond the saddle member, the saddle member having a seat portion for the base, and means on the saddle member outwardly of and engaging the base for preventing relative longitudinal movement of the base and saddle member while permitting relative rotary movement thereof.

In testimony whereof I affix my signature.

KENT A. HAWLEY.
